UNITED STATES PATENT OFFICE.

FRANCIS W. TULLY, OF BROOKLINE, MASSACHUSETTS.

FABRIC FOR MATS, RUGS, &c.

1,223,537.

Specification of Letters Patent.

Patented Apr. 24, 1917.

Application filed November 26, 1915. Serial No. 63,355.

To all whom it may concern:

Be it known that I, FRANCIS W. TULLY, a citizen of the United States, and resident of Brookline, in the county of Norfolk and State of Massachusetts, have invented new and useful Improvements in Fabric for Mats, Rugs, &c., of which the following is a specification.

My invention relates to rugs, carpets, mats, and other coverings, one object of my invention being to prevent such a covering placed upon a slippery surface, for instance a polished floor, without fastening means, from sliding under use. Other objects of my invention are to provide improved protection against wear adaptable to the under surface of woven carpets, rugs, mats and other fabrics adapted to use as floor coverings.

Further objects of my invention are to provide a structure for such rugs, carpets or other textiles applicable either during manufacture or to previously made articles, which will present a frictional surface capable of maintaining a detached section of the carpet or other textile in place during use upon varnished or polished floor surfacings.

Under modern conditions, most floor coverings are not intended to be fastened down under tension, but rest loosely upon the floor, often being made up into mats or rugs, or woven in units as rugs of various sizes. Such rugs in use on a slippery or polished floor are often the cause of serious accidents and annoyance to their users by reason of the lack of friction between the under surface of the rug and a polished floor. I have discovered that this difficulty may be permanently avoided by providing

on the under surface of such floor coverings points of contact with the floor presenting a higher coefficient of friction with respect to the floor than the projecting parts of the back surface of such carpets, rugs, etc. provided by the hard smooth yarns of their common and well-known structure. I have also discovered that a relatively small area in comparison with the whole area of the back surface of such a carpet or rug, if made sufficiently frictional, will serve to retain the whole carpet or rug against slippage under any usual strain, especially if the distribution of the relatively frictional points or areas is such as to cause them to lie with relative frequency in every direction of the under surface.

I will now explain my invention in connection with the accompanying drawings, in which—

Figure 1 is a longitudinal section of a part of a warp-pile fabric of the Axminster type showing one application of my invention:

Fig. 2 is a cross section on line 2—2 of Fig. 1;

Fig. 3 is a view similar to Fig. 1, showing a modification;

Fig. 4 is a fragmentary cross section in the direction of the weft showing another modification;

Fig. 5 is a cross section in the direction of the weft illustrating another form of the invention;

Fig. 6 is a view similar to Fig. 1 illustrating a further modification;

Fig. 7 is a view illustrating a yarn adapted to be employed in producing fabrics corresponding to my invention;

Fig. 8 is a cross section in the direction of the weft illustrating one employment of the yarn shown in Fig. 7;

Fig. 9 is an elevation of the back side of a fabric showing a form of my invention applicable as an addition to existing fabrics; and

Fig. 10 illustrates on an enlarged scale one structure by which existing fabrics may be made to conform to my invention.

While I have shown my new article of manufacture woven as an Axminster carpet fabric of a well-known form, it will be understood that such showing is illustrative only, my invention being adapted to any woven fabric suitable for use as a covering, as for a floor or table.

Referring now to Fig. 1, in the customary structure pile tufts 1 forming the face of the fabric are held upon a base or body comprising strong structural warps 2, stuffer warps 3, and strong weft yarns 4, the under surface resting upon the floor in use usually being made up of the wefts 4 bowed out by the stuffer warps 3 between their places of engagement by the warps 2. Carpets and rugs of this general structure, of which there are many variants well-known to those skilled in the art, therefore stand upon a number of separated feet, necessarily of a hard, slippery yarn. In all carpets and rugs with which I am familiar, except double-faced pile fabrics, the under surface is some form of reticulation presenting higher

2
places which form the only frictional contact with the floor.

In one form of my invention, as shown in Fig. 1, one of the structural yarns brought by the structure of the weave, whatever that may be, to the back surface at frequent intervals is so treated as to cause it to stick to the floor. Preferably I treat a yarn or yarns 5 with an adherent sticky substance forming a frictional coating on the yarn. Such a coating, which may if desired penetrate the body of the yarn, may be formed by immersion or by spraying or padding on any suitable gummy or sticky composition, such as a solution or compound of unvulcanized or partially vulcanized rubber in naptha or any suitable solvent, or such a composition rendered fluid by heat; or I may employ any of the well-known compositions of matter having as an ingredient an oxidized oil; or a colloid substance such as bichromated glue, gum, gelatin, wax or the like; or a substance composed of a vegetable oil brought to a viscous or solid state by suitable combined reagents and vulcanizing or viscolizing treatments. In general, any compound or mixture suitable for adhesive plasters or adhesive tapes having the characteristic of adhesion to hard, smooth surfaces, preferably without leaving particles on the surface when removed, may be employed.

As illustrated in Fig. 1, the weft 4 is exchanged during every sixth pick for a treated weft 5 whereby, as illustrated at 6, the bowed out portions at the back of the fabric at every third reticulation are of the sticky covered yarn. While I have illustrated this numerical relation, it will be understood that the entire weft may be treated, if desired, or that the separation of the treated wefts by untreated wefts may be greater than or less than illustrated, the treated weft for instance being thrown across the open shed at every twelfth or every twentieth pick. I have shown the weft returned on the next pick, Fig. 1.

I may, as shown in Fig. 3, employ a continuous untreated weft 7 and throw the treated weft 5 through the open shed along with the untreated weft at such intervals as desired, for instance as illustrated, at every sixth pick, returning the treated and untreated weft together during the following 55 pick.

In some cases it is more convenient for manufacture to avoid weft changes, and in that case I may employ the expedient illustrated in Fig. 4 in which one of the stuffer warps is a coated yarn 5, and is shed out at the back of the fabric along with the structural warp 2, at intervals of a plurality of picks, so as to project from the back face of the fabric.

65 I may secure much the same result, as

illustrated in Fig. 6, by providing one of the stuffer warps 3, as shown at 30, with a coating of the frictional material, and holding said warp with little tension so that successive beat-up slackens and projects it in loops, as illustrated at 31, which may be caused to lie on the back of the fabric by properly positioning the warp 30 with respect to the other stuffer warps 3, as will be understood by weavers. In some cases I prefer to so weave the base fabric carrying any suitable pile formation as to cause the warps to rest on the floor, and as illustrated at Fig. 5, in this case an occasional warp 12 may be treated with the described frictional coating.

When making the structure of Fig. 1 or the structure of Fig. 4 of Fig. 5 or Fig. 6, for economy of the sticky addition to the yarn or for ease in handling and for other purposes, I may employ a treated yarn as illustrated in Fig. 7 having a coating 50 applied at intervals and leaving intervening sections 10 untreated.

If the sections 50 are more than twice the width measured along the weft and the yarn illustrated in Fig. 7 is employed as the weft, no particular relation of treated or untreated parts to the warp need be observed, since every section having a coating 50 will necessarily reach the back surface at some part of its run across the fabric and back. Treated sections 50 more than twice the width of the fabric may thus be scattered with a desired length of untreated space 10 between them, and the whole wound for the weft, weaving with such a weft necessarily resulting in the generic structure illustrated in Fig. 1. It will be obvious without further description that an occasional coating when the treated yarn is in the position illustrated in Figs. 4, 5 and 6 will equally be effective. Fig. 8 illustrates, for instance, a structural weft 4 having the bare spaces 10 and the coatings 50.

110 My invention is applicable not only to carpets and rugs to which it can be applied during manufacture, but may be applied to existing carpets and rugs, such as Oriental rugs or rugs in stock, unsalable because of their slippery qualities. As illustrated in Fig. 9, I have shown the back surface of such an existing Oriental or other carpet or rug having a yarn 20 coated either throughout its length or in the manner illustrated in Fig. 7, attached to its surface by a sewing operation, which may be done by hand or machine, for instance as illustrated in said figure at a. The yarn 20 is sewn zig-zag under any part of the reticulation at the back of the rug, passing into the structural body at 21 and lying on the under surface between the points 21. As shown at b the zigzag stitches may be of a different slope from those shown at a, and in some cases I

may attach the yarn 20 as illustrated in Fig. 10 by a row of enchain'd stitches of an entirely separate sewing thread 24 which passes at the dotted runs 25 into the structural body of the carpet. As well understood by those skilled in the art, such a sewed structure as illustrated in Fig. 10 may be made by a sewing machine having a penetrating needle, eye-pointed, a detaining looper for enchain'g the thread carried by the needle, as at 26, and a thread-carrying looper for the thread 20 to distribute it as shown in said figure, whereby it is attached upon the surface of the article, thread 25 only penetrating any part of the body of the carpet or rug. Such stitching is familiar in gloves, underwear, and for over-edging carpets and other cloths.

One advantage of the structures illustrated in Figs. 9 and 10, which inures also to the structure illustrated in Fig. 4, is a slight increase of tension at the back or under surface of the fabric, which causes it to curl downward at the corners and thereby lie flat on the floor without tendency to roll up at the corners.

What I claim is:

1. A fabric adapted for a floor covering, including a textile or fibrous element having an adhesive surface and exposed at intervals on one face of the fabric.

2. A fabric for use as a covering for polished surfaces having incorporated therewith a yarn having a sticky covering adapted to adhere to said surface, the remainder of the fabric not being sticky.

3. A woven textile mat, rug or other covering having a yarn exposed at one surface at intervals, said yarn having an adhesive coating.

4. A textile mat, rug or other covering having on one face a pile and on the other face exposed runs of a yarn having a relatively high capacity for adhering to polished surfaces.

5. An inelastic woven fabric having a fibrous structural yarn exposed on one face

only at intervals, said yarn having an adhesive surface whereby to prevent slippage of the fabric when said face is laid upon a polished surface.

6. A woven fabric having one of its yarns thrown to one face at intervals, said yarn bearing an adhesive substance to determine adhesion of its exposed portions to a surface supporting said fabric.

7. A fabric having as an exposed element a yarn having incorporated therewith a sticky substance adapted to adhere to polished surfaces.

8. A fabric having an exposed fibrous yarn bearing an adherent composition of matter adapted to cause the said yarn to cling to polished surfaces.

9. A woven textile mat or rug having as an element exposed at intervals on one surface a yarn treated by covering with a composition containing an adhesive gummy substance, substantially as described.

10. A woven carpet or rug fabric comprising a wear-surface and a body, one face of the body being adapted to rest on the floor, wherein yarns forming a part of the woven structure distributed over the surface of the fabric and touching the floor in use are rendered adhesive, as by coating with an adhesive substance, the remainder of the fabric being non-adhesive.

11. A woven pile fabric having structural warp and weft yarns and stuffer yarns forming a body bearing the pile, in which an occasional one of said yarns exposed on one face of the body bears an adhesive substance.

12. A fabric adapted to adhere to a supporting surface comprising a yarn occasionally exposed on the surface of the fabric, said yarn having at intervals an adherent coating adapted to stick to said supporting surface.

Signed by me at Boston, Massachusetts, this 23rd day of November, 1915.

FRANCIS W. TULLY.
